UNITED STATES PATENT OFFICE.

EDWARD B. ROBY, OF NORTH TROY, NEW YORK, ASSIGNOR TO S. AND R. FOLDING MACHINE COMPANY, INC., OF GREEN ISLAND, NEW YORK, A CORPORATION OF NEW YORK.

MACHINE FOR FOLDING THE EDGES OF TEXTILE AND SIMILAR ARTICLES.

Application filed August 29, 1925. Serial No. 53,246.

The present invention has particular reference to and is specially adapted for operating in conjunction with a machine for folding the edges of textile and similar articles, such as collars for personal wear, machines of this general character being shown in my prior Patents, #1,260,060, dated March 19, 1918, and #1,592,045, dated July 13, 1926.

The present invention has among its principal objects: to increase the speed of operation; to simplify the mechanism and reduce the cost of upkeep; to adapt the machine for individual motor drive; to reduce the operating cost of the machine; and to facilitate the control of the action of the machine.

Drawings.

Figure 1 is a sectional elevation of a machine of the character mentioned, constructed and arranged in accordance with the present invention.

Figure 2 is a horizontal section of the driving mechanism, the section being on enlarged scale and taken as on the line 2—2 in Figure 1.

Figure 3 is a vertical section of the driving mechanism, the view being on enlarged scale, and the section being taken as on the line 3—3 in Figure 2.

Figure 4 is a detailed view in section of the driving mechanism, the section being taken as on the line 4—4 in Figure 2.

Figure 5 is a detailed view in section showing a portion of the rewinding mechanism, the view being taken as on the line 5—5 in Figure 2.

Figure 6 is a detailed view of the ratchet and pawl for cooperating with the rewinding mechanism.

Figures 7 and 8 are details of a part of the machine showing the mode of operation.

Figures 9, 10, 11 and 12 are schematic, each showing a layout of the action controlling cam and the power lever affected thereby, the successive figures showing the successive steps in the operation of the mechanism and its effect upon the power lever.

Description.

Referring to Patent #1,592,045 above noted, it will be seen that the operating elements are caused to function in accordance

with the reciprocation of a shaft designated by the letter *e* in said patent. In the present application this shaft is substituted by the plunger 20. The plunger 20 is provided on the opposite sides thereof with recesses 21 and 22, respectively. The recesses 21 and 22 are identical with those indicated in Patent #1,592,045, and cooperate in the same manner therein indicated with the rocking levers 23, these levers being indicated in said patent by the letters, *K* and *M*.

It will be noted the levers 23 have short arms 24, at the ends whereof, are rollers which track on the sides of the recesses 21 and 22 and of the plunger 20. The operation and function of the parts in Patent #1,592,045 corresponding with the levers 23 and parts associated therewith, is fully described in said patent. The difference between the construction in said patent and the present application may be said to exist principally in means for moving the plunger 20, and means for holding the levers 23 in such position to be released simultaneously. The first of the said means consists in substituting for the power cylinder and operating means therefor of the patent, the bell crank 25 and means for operating the same to reciprocate said plunger.

The second means above referred to will be found in the employment of the toggle links 26 which are pivotally connected to each other. The links, 26, are locked in straight lines with respect to one another by means of square shoulders, 27, on the ends of said links, as shown in Figures 7 and 8.

From the disclosure with reference to the levers 23 and the links 26, it will be seen that when the crank 25 is drawn down from the position shown in Figure 1 of the drawings, the levers are successively rocked, due to the difference in lengths of the recesses 22 and 21, respectively.

By reference to Figure 1 of the drawings, it will be seen that when the plunger 20 is depressed, the lever having a short arm 24 resting in the recess 22 is rocked ahead of the lever 23, having the short arm 24, in the recess 21. It is when the latter lever 23 is rocked by the short arm 24 thereof passing out of the recess 21, that the links 26 are straightened and locked.

When now the plunger 20 is returned to its initial position, it will be seen that though the end of the short arm 24 aligns with the recess 21, the links 26 will prevent the lever 23 from rocking, or the short arm thereof dropping into the recess 21. When, however, by the further movement of the plunger 20 the short arm 24 cooperating with the recess 22 is brought opposite said recess 22 the pin 24^a on the end of the short arm of the left hand lever 23 strikes the links 26, and the locked position of the links 26 is broken and both of the levers 23 are permitted to rock to their initial position. 10 In passing I would say that the operation of the elements connected with the levers 23 is such as to be benefited by the delayed release of the first mentioned lever and by the simultaneous release of both levers. 15 The bell crank 25 is mounted on a pivot shaft 28 the bearings for which are bracketed from a collar 29, which is adjustably fixed on the lower extension 30 of the plunger 20. The plunger 20 and extension 25 thereof is guided in perforations formed in the frame 31 and bracket 32, shown best in Figure 1 of the drawings. The lower end of the bell crank 25, is pivotally attached to a lever arm, 33, and the bell crank, 25, collar, 29, and plunger, 20, are drawn down when the lever arm, 33, is rotated from the position shown in Figure 1 in the direction indicated by the arrow in said figure. As a preliminary to this action it 35 will be noted, however, that the bell crank 25 rocks on the pivot shaft 28 to lift the outer end of the arm 25'. The arm 25' is operatively connected through the push rod 34, the link 35 and 40 the set screw 36 with the pressure arm 37 of the collar edge folding machine shown in the drawings. It will be noted that when the pivot 28 which connects the bell crank 25 with the crank arm 33, has reached a 45 point in its arc of movement where it starts to descend appreciably, the extremity of the arm 25' has been lifted to rock the arm 37 to place the foot plate 39 in the path of the short end 23' of the rocking lever 23 at the 50 back of the machine.

At the very beginning of the descent of the shaft 28, the plunger 20 engages the short arm 24 of the rocking lever 23 with the result that the extension 23' is placed 55 in the path of the foot plate 39. During the remainder of the movement of the bell crank 25 and parts associated therewith, the pivot 40 may be said to constitute the fulcrum of the bell crank 25 and the center 60 around which it moves, all thrust imparted thereto being resisted by the rod 34 and link 35.

In the operation of the driving mechanism, the crank arm 33 is rocked one half 65 of a complete revolution, or from the posi-

tion shown in Figure 1 of the drawings above the driving shaft 41, to a position directly below said shaft.

The arm 33 is integrally connected with a lever arm 42. The lever arm 42 is shown best in Figure 2 of the drawings where it will be seen it has an elongated bearing 43 on the shaft 41. At the outer extremity of the lever arm 42, the said lever arm provides a bearing for a short shaft 44. The shaft 44 is restrained from movement in one direction by a pawl 45 and a ratchet wheel 46 mounted at one end of said shaft and on the pad 47 at the extremity of the lever arm 42. This construction can be best seen 75 at Figure 6 of the drawings.

It is obvious that the pawl 45 on the pad 47 permits the shaft 44 to rotate freely in one direction. The said shaft 44 is impelled to move in the said direction by a spring 49. 85 The spring 49 is anchored at one end to the said shaft and the other to the hollow wheel 50, the outer edge whereof is serrated to frictionally engage the serrated channel 51 of the internal gear ring 52, as 90 shown best in Figure 2 of the drawings. The shaft 44 forms a core on which the spring 49 is wound. The shaft has an extended pindle 53 which extends into the space between the internal gear ring 52 and 95 the external gear wheel 54, which construction may be seen best in Figure 4 of the drawings.

The pindle 53 has integrally mounted thereon, a single gear tooth 55 which is 100 adapted to mesh with the teeth on the ring 52, or the wheel 54, in accordance with the disposition of the shaft 44.

The shaft 44 is rotated constantly in one direction being impelled thereto by the 105 spring 49 whenever the shaft is released by the escapement 56. The escapement 56 is mounted in a housing 57 being pivotally mounted therein by means of the bolt 58, as shown best in Figure 3 of the drawings. 110 The escapement 56 has a head 59 that is designed to move successively into the path of the abutments 60, 61 and 62.

The two abutments 60 are shown in Figure 2 of the drawings as in the same plane, 115 while the abutments 61 and 62 are disposed in planes at opposite sides thereof. The result of this construction is that when the escapement 56 is lifted from the path of either of the abutments 60, it passes into the path of one or other of the abutment 61 or 62. The immediate result of this action is that the shaft 44 is rotated by the spring 49 and arrested in accordance with the abutment 61 or 62 with which the head 59 of the escapement 56 is engaged, and the tooth 55 on the pindle 53 engages the teeth of the ring 52 or the wheel 54 to travel thereover with the said ring or wheel carrying the free end of the lever arm 42 in accordance with 125 130

the movement of the member engaged, which members it will be observed by reference to Figure 4 of the drawings, and the arrows shown thereon, are constantly travelling in opposite directions, being thereto impelled by means of the driving pinion 68 herein-after described.

From the foregoing it will be understood that whenever the escapement 56 is so disposed that the head 59 thereof engages either of the abutments 60, the pintle 53 and the tooth 55 thereof are positioned as shown in Figure 4 of the drawings, where the said tooth is engaged with neither the ring 52 or the wheel 54 which therefore continue to rotate without affecting the lever arm 42 and parts associated therewith.

It will be further observed that when the escapement is rocked to engage either the abutment 61 or the abutment 62, the pintle 53 is rotated to engage one or other of the said ring 52 or wheel 54 to move therewith to the end that the lever 42 is carried either from the position shown in Figure 1 of the drawings to a position at the opposite side of said Figure 1 or one-half of a complete rotation about the shaft 41.

The rocking of the escapement 56 is manually controlled. The foot lever 64 is used for this purpose. The inner end of the lever 64 is connected by a link 65 to a short arm 66 on the shaft 67.

The shaft 67 is rotatively mounted in suitable bearings and is provided at the opposite end thereof from the short arm 66, with a gear segment 68 which is rocked in correspondence with the rocking of the shaft 67 or the movement of the lever 64.

The segment 68 is suitably and permanently engaged by a pinion 69 rotatively mounted on the shaft 41. Rigidly connected with the pinion 69 is a cam wheel 70. The wheel 70 has cut therein a cam groove, said groove having levels 71, 72 and 73, the first of which will be termed the neutral levels and the latter, the active levels. These levels and their relation to the ring 52, wheel 54 and pintle 53, can best be seen in the diagrammatic figures 9 to 12 inclusive.

The escapement 56 is controlled by the cam groove in the wheel 70, and to this end the tail of the escapement 56, has a bolt 74, the end of which rides in the cam groove of the wheel 70.

From the foregoing it will be seen that when the operator desires to rock the lever arm 42 from the position shown in Figures 1 and 9, to the position shown in Figure 11, thereby first rocking the bell crank 25 to lift the free end of the arm 25' and pull rod 34 connected therewith, he depresses the foot lever 64, rocking thereby the shaft 67 and segment 68 connected therewith.

As above mentioned, the first portion of the lever 42 and crank arm 33 connected

therewith rocks the bell crank 25 on the shaft 28 as a fulcrum or pivot, with the result that the pressure arm 37 and parts associated therewith are lowered from the position shown in Figure 1 of the drawings to the active position of the machine. The arm 37 being so disposed, the continued movement of the crank arm 33 draws the bell crank 25 downward with the collar 29 and parts associated therewith, causing the levers 23 and plunger 20 to function in a manner better set forth in Patent #1,592,045.

It will be observed that when the foot lever 64 is depressed, the segment 68 is rocked in the direction shown by the arrow associated therewith in Figure 1. The pinion 69 and the cam wheel 70 are thereby rotated on the shaft 41 to move the cam level 73 into the upper or vertical position in correspondence with the disposition of the bolt 74, as seen in Figure 1 of the drawings. The escapement 56 is rocked on the bolt 58 to release the ratchet abutment 60 and to move the same into the path of the abutment 61.

As soon as the head 59 of the escapement 56 passes out of engagement with the abutment 60, the spring 49 rotates the shaft 44 until arrested by the engagement of the abutment 61, with the head 59. The shaft 44 being thus rocked, rotates the pintle 53 to place the gear tooth 55 in engagement with one of the teeth of the ring 52, as shown in the diagram in Figure 10.

As the ring 52 is continuously rotating, and the tooth 55 is stationarily engaged therewith, the shaft 44 and lever 42 connected therewith are gyrated around the shaft 41 which also forms a bearing for the ring 52. It will now be observed that the wheel 70 remains stationary, the operator keeping his foot on the lever 64. The result is that the bolt 74 travels through the groove in the wheel 70 from the level 73 to the level 71 through the inclined section connecting the same.

When the bolt 74 is thus moved from the level 73 to the level 71 the escapement 56 is rocked to release the abutment 61 and the spring 49 then rotates the shaft 44 until the head 59 of the escapement is engaged by the abutment 60, when it will be found that the pintle 53 has been rocked to disengage the tooth 55 from the ring 52, the said pintle and the end of the lever 42 with which it is connected having been carried for approximately $\frac{1}{2}$ a complete gyration about the shaft 41 or from the position of the lever 42, shown in Figure 9 of the drawings to the position of the said lever shown in Figure 11 of the drawings. It is desired in this connection that it be understood that the level 71 is a short level, while the levels 72 and 73 are relatively long, each equalling a travel space for the bolt 74 equivalent to approxi-

mately the $\frac{1}{2}$ revolution of the ring 52 and wheel 54, thus insuring the rocking or gyration of the lever 42 as described from either of said positions.

- 5 The lever 42 having been thus carried from the position shown in Figure 9 to the position shown in Figure 11 no further action will occur as long as the lever 64 is depressed. When, however, the lever 64 is released, the spring 75 lifts the free end thereof carrying the link 65 with the result that the segment 68 is rocked to its original position, the wheel 70 being reversely rotated to move the bolt 74 into the cam level 72.
- 10 This arrangement causes the escapement 56 to release the second abutment 60 and to engage the abutment 62, the spring 49 being now permitted, rocks the shaft 44 and the pintle 53 connected therewith to engage the 15 tooth 55 thereon with the teeth of the wheel 54. The wheel 54 travelling as it does in a direction reverse of that travelled by the ring 52, the lever 42 is rocked or gyrated back to the original position from which it 20 moved, or to the position shown in Figure 9. Again the bolt 74 is carried out of the level 72 back to the level 71 with the result that the escapement 56 is again rocked out of engagement with the abutment 62 to be re-engaged by the abutment 60, originally engaged.

The prime mover for the mechanism is an electric motor 76 of usual construction. The motor 76 has mounted on the armature shaft 77 thereof, a pinion 78, the teeth whereof are engaged with the teeth of a larger gear wheel 79, which is mounted rigidly on the shaft 80. At the outer end of the shaft 80 is mounted the pinion 63 that continuously operates to 40 drive the ring 52 and the wheel 54 in the relatively opposite directions.

It will be understood that the motor 76 and the transmission mechanism embodying the pinion 78, wheel 79 and pinion 63, are driven continuously in one rotary direction.

By means of the arrangement of the mechanism disclosed in Figures 1, 7 and 8, the arms 23 and mechanism associated therewith are operated to function successively. The 50 short arm 24 of one of said levers falling into the recess 21 in precedence of the short arm 24 of the other of said levers falling into the recess 22.

On the down stroke of the plunger, the 55 left-hand lever, 23, as seen in Figure 1 is first rocked by the short arm 24 thereof passing out of the short recess 22. The right hand lever 23 is rocked shortly afterwards when its short arm, 24, passes out of the recess 21. The folding members operated by the levers, 23, are therefore operated and moved in successively with a time interval between their movements. When the two 60 short arms of the levers have passed out of their recesses, the toggle links, 26, are neces-

sarily straightened and locked. Therefore on the up-stroke of the plunger no rocking of the levers, 23, occurs until the short arm, 24, of the left-hand lever 23 strikes the recess, 22, when the left-hand lever 23 rocks and the pin 24a on the end of the short arm 24 thereof strikes the links, 26, breaking the toggle and permitting the right hand lever 23 to rock. Thus on the upstroke of the piston the levers 23 are substantially simultaneously rocked and the folding members simultaneously withdrawn.

I claim:

1. In a machine as characterized a driving mechanism comprising a reciprocating member; a crank arm operatively connected with said member; means for rocking said crank arm, said means embodying rotary concentric members disposed in spaced relation and power-driven continuously in relatively opposite directions; a lever arm operatively connected with said crank arm and adapted for alternately engaging said concentric members to be move thereby.

2. In a machine as characterized a driving mechanism comprising a reciprocating member; a plurality of rotary members concentrically disposed in substantially the same plane, one of said members having an inwardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members.

3. In a machine as characterized a driving mechanism comprising a reciprocating member; a plurality of rotary members concentrically disposed in substantially the same plane, one of said members having an inwardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members; and automatic means for rotating said rocking members; and stopping mechanism for arresting the rotation of said rocking member in opposite working positions.

4. In a machine as characterized a driving mechanism comprising a reciprocating member; a plurality of rotary members concentrically disposed in substantially the same plane, one of said members having an in-

wardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members; and automatic means for rotating said rocking member; and stopping mechanism for arresting the rotation of said rocking member in opposite working positions, said stopping mechanism embodying a cam member having oppositely extending cam risers for operating said stopping mechanism.

5. In a machine as characterized, a driving mechanism comprising a reciprocating member; a plurality of rotary members concentrically disposed in substantially the same plane, one of said members having an inwardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members; and automatic means for rotating said rocking member; and stopping mechanism for arresting the rotation of said rocking member in opposite working positions, said stopping mechanism embodying an escapement mechanism, and a cam member for operating said escapement mechanism for releasing said automatic mechanism for predetermined amounts of rotation of said rotary members.

6. In a machine as characterized, a driving mechanism comprising a reciprocating member; a plurality of rotary members concentrically disposed in substantially the same plane, one of said members having an inwardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members; and automatic means for rotating said rocking member; and stopping mechanism for arresting the rotation of said rocking member in opposite working positions, said stopping mechanism embody-

ing an escapement mechanism, and a cam member for operating said escapement mechanism for releasing said automatic mechanism for predetermined amounts of rotation of said rotary members, said amounts corresponding with the quarter revolutions of said rocking member, whereby the same is placed, successively, in engagement with one of said rotary members; then out of engagement with both rotary members; and then in engagement with the other rotary members.

7. In a machine as characterized, a driving mechanism comprising a reciprocating member; a plurality of rotary members concentrically disposed in substantially the same plane, one of said members having an inwardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members; automatic means for rotating said rocking member; stopping mechanism for arresting the rotation of said rocking member in opposite working positions, said stopping mechanism embodying an escapement mechanism, and a cam member for operating said escapement mechanism for releasing said automatic mechanism for predetermined amounts of rotation of said rotary members, said amounts corresponding with the quarter revolutions of said rocking member, whereby the same is placed successively in engagement with one of said rotary members; then out of engagement with both rotary members; and then in engagement with the other rotary members; and manually operated means for rotating said cam member, said means embodying a mechanism for rotating said cam from the neutral position thereof in opposite directions successively for engaging said rocking member with one or other of said rotary members, said cam being held in adjusted position by said manually operated means while said stopping mechanism is moved retractively thereover to the neutral position thereof for automatically disengaging said rocking member with said rotary member.

8. In a machine as characterized, a driving mechanism comprising oppositely moving power members; connecting mechanism for engaging said power members alternately for imparting movement to said machine; said connecting mechanism embodying a rocking member for engaging said power member; and a three rise cam for rocking said member into engagement when moved 125 130

from the neutral rise to the positive rise to be returned to the neutral rise in the course of the movement with said power member for automatically disengaging said power member.

9. In a machine as characterized, a driving mechanism comprising a reciprocating member; a plurality of rotary members concentrically disposed in substantially the same plane, one of said members having an inwardly faced edge, and the other an outwardly faced edge, said edges being in spaced relation; a lever arm pivotally mounted concentric with said members and pivotally connected with said reciprocating member; means for connecting said lever and said rotary members, said means embodying a rocking member pivotally connected with said lever arm and extended between said rotary members to be rocked for engaging alternately the edges of said rotary members; and au-

tomatic means for rotating said rocking member, said means embodying an escape-
ment member having abutments, and a
spring for rotating the same in one direc-
tion when permitted thereto, and means em-
bodying one of said rotary members for re-
winding said spring. 25

10. In a machine as characterized, a driv-
ing mechanism comprising a reciprocating
member, said member having oppositely dis-
posed cam-like recesses of unequal length;
and a plurality of operating lever arms,
each having a short arm for engaging said
recesses, and resilient means for tensioning
said short arms to fall in said recesses, and
toggle means for mutually controlling the
movement of said short arms to delay the
operation of one of said levers in corre-
spondence with the other of said levers. 30 35

EDWARD B. ROBY.
